US00D541740S

(12) **United States Design Patent** (10) **Patent No.:** **US D541,740 S**
Tsai et al. (45) **Date of Patent:** **** May 1, 2007**

(54) **BATTERY CHARGER FOR ELECTRIC TOOL**

(75) Inventors: **Kim Y. C. Tsai**, Taichung Hsien (TW);
Ju-Chien Chen, Taichung (TW);
Fu-Tasi Wu, Taichung County (TW);
Tung-Chin Kuo, Taichung County (TW);
Hsiang-Po Huang, Taichung County (TW)

(73) Assignee: **Mobiletron Electronics Co., Ltd.**,
Taichung Hsien (TW)

(**) Term: **14 Years**

(21) Appl. No.: **29/259,426**

(22) Filed: **May 9, 2006**

(51) **LOC (8) Cl.** **13-02**

(52) **U.S. Cl.** **D13/108**

(58) **Field of Classification Search** D13/107-110,
D13/118-119, 184; D14/251, 253, 432, 434;
320/107-115

See application file for complete search history.

(57) **CLAIM**

The ornamental design for a battery charger for electric tool, as shown.

DESCRIPTION

FIG. 1 shows a perspective view of the present design.
FIG. 2 shows a right side elevational view of the present design.

FIG. 3 shows a top plan view of the present design.

FIG. 4 shows a front elevational view of the present design.

FIG. 5 shows a bottom plan view of the present design.

FIG. 6 shows a left side elevational view of the present design; and,

FIG. 7 shows a rear elevational view of the present design.
